(57) **CLAIM**

The ornamental design for vehicle-wheel front face, as
shown and described.

DESCRIPTION

FIG. 1 is a perspective view of a vehicle-wheel front face
according to my new design;

FIG. 2 is a front elevational view thereof;

FIG. 3 is an second embodiment of my design wherein a
forward portion of the front face is rotatable with respect to
a rim of the wheel, the alternative embodiment in one
position corresponding to FIGS. 1 and 2, and being shown
in FIG. 3 in a slightly different rotational position; and,
FIG. 4 is a side elevational view of both embodiments.
Portions of the wheel depicted in broken lines are for
illustrative purposes only, and form no part of the claimed
design.
